UNITED STATES PATENT OFFICE

2,423,847

OIL SMOKE GENERATOR

Howard E. Norton, Baltimore, and John R. Bond,
Colora, Md.

Application July 10, 1942, Serial No. 450,384

3 Claims. (Cl. 158—91)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to the production of smoke screens, and has as its primary object the provision of a device which may be used to advantage for producing screening smokes for the purpose of screening troop movements, canals, depots, and other desired objects or area, the hiding of which may be required for military or other purposes.

Particularly as regards the military, and in times of war, the uses of smoke screens and the situations under which they are employed are many and varied. Consequently to be thoroughly and efficiently effective devices used for producing screening smokes for military purposes must possess certain requisites.

It is, therefore, the broad aim of this invention to provide a smoke producing instrumentality that will meet all the exacting requirements of such a device when used in situations arising and under conditions encountered in military operations, and is free of those objections hereinafter noted against the various methods and devices heretofore available for producing smoke screens.

Various types of smoke generators, such as smudge pots, orchard heaters, and the like, have been proposed and used for the purpose stated, but all of them have been found objectionable for any one or more of a variety of reasons. In general, cumbersome structure, tendency to emit flame to a very marked degree, inability to produce durable smoke clouds continuously for relatively long periods of time, likelihood of becoming adversely affected by momentarily existing atmospheric conditions, and generally a lack of adequate equipment for controlling and varying the smoke-cloud production at will, are some of the major drawbacks militating against the various types of smoke generators and methods heretofore at the disposal of the military forces.

The smoke generator constituting the present invention will be found possessed of those above enumerated features the lack of which militates against present smoke generators and the possession of which is a highly desirable requisite when smoke generators are used as contemplated by this invention.

The features of the invention, combining to present a smoke generator having all the requisites desirable for military use and capable of attaining the objects of the invention, will best be

2

understood from a consideration of the following detailed description, taken in conjunction with the accompanying drawings, in which:

Figure 1 is a vertical, sectional view through a smoke generator embodying the features of this invention;

Figure 2 is a horizontal sectional view taken substantially on line 2—2 of Figure 1;

Figure 3 is an elevational view of an air inlet tube;

Figure 4 is an elevational view of an air inlet valve member; and

Figure 5 is a top plan view of the assembled smoke generator.

In the embodiment illustrated, the smoke generator of this invention consists essentially of a receptacle or oil pot 5, a stack 6, a hood 7 for the stack, an air inlet tube 8 for pot 5, and a valve assembly 9 for the tube 8.

Briefly described, the operation of the illustrated form of the invention is as follows: The oil pot 5 is filled with fuel, preferably oil 10, to substantially the level indicated in the drawings. Lid or cover 11 for pot 5 is then positioned on the latter, after which the remaining parts of the generator are assembled in any preferred order. Prior to adjustment of the valve member 12 the oil contents 10 of pot 5 are ignited by inserting a torch or other suitable type of igniter downwardly into the pot, the burning end of the torch passing downwardly of air inlet tube 8 in a manner believed obvious.

The stack 6 performs the function of conveying to the outer atmosphere the smoke generated by the fired fuel in the oil pot 5. The valve member 12 is adjusted to regulate the intake of air through inlet tube 8. In this connection it may be observed that by removing valve member 12 the required maximum amount of air is supplied to pot 5 for effecting initial combustion. As little time and effort are required for removal and adjustment of valve member 12, the placing of the generator in effective operation is quickly and easily accomplished, and requires but little skill on the part of the operator.

The wall of stack 6 is imperforate throughout the length of the stack, and by reason of this fact all the generated smoke passes upwardly to emanate from the generator only at the top of the stack. As a result there is no loss of smoke in the passage thereof through the stack, and as would result were the stack wall perforated as is generally the case with stack equipped smudge pots, orchard heaters, and similar types of smoke generators. Consequently the smoke issuing from

the generator of this invention is in the form of a dense cloud best suited to providing an opaque protective screen. Then too, by reason of the imperforate stack, combustion takes place only within oil pot 5, so that no flame is emitted from the generator. In other types of generators, and by reason of the perforated stacks, generally, thereof, a substantial amount of flame is emitted, an undesirable feature from the standpoint of safety and other obvious factors.

The lid 11 fits tightly on pot 5 and is provided with a neck 13 as shown. Lid 11 is so shaped as to form a combustion chamber 14 for the pot 5, and from which the generated smoke rises to pass to the atmosphere through stack 6.

To protect the fuel contents of pot 5 from the elements, and to direct the smoke outwardly in substantially horizontal planes from the generator, there is provided hood or cap 7. Cap 7 is substantially of frustro-conical form and is supported by uprights 16. Uprights 16 are secured at one end thereof to the underside of cap 7 in any suitable manner, as by being welded thereto, and at an opposite end are, in a similar manner, secured to a band or annulus 17. Band 17 is adapted to be sleeved onto either the upper end of stack 6 or onto the upper end of an adapter 18 as may be found most desirable. It will of course be understood that the diameter of band 17 will be determined by the diameters of the respective upper ends of stack 6 and adapter 18.

When used, adapter 18 is mounted upon the upper end of stack 6, and is spaced circumferentially therefrom by means of spacers 19. Spacers 19 also serve to secure within the confines of the bottom end of the adapter a mounting band or annulus 20 adapted to be sleeved onto stack 6 as shown.

Smoke passing up through the adapter 18 tends to produce a suction that draws air from the surrounding atmosphere up into the adapter to commingle with the smoke. Thus the adapter serves to provide a mixing chamber, and the air so delivered to the smoke column has a cooling effect thereon and thereby increases the gravity thereof, as a result of which the smoke issuing from the generator tends to descend and form a wall or screen touching the ground and rising therefrom to be utilized as a protection for, or the hiding of, troop movements, canals, depots and other desired objects or areas.

To accommodate and support air inlet tube 8 pot lid 11 is provided with an aperture with which is aligned a tube supporting seat 21. Seat 21 is in the form of a tubular member that has one end thereof snugly fitted within the aforementioned lid aperture and secured in position on the lid in any suitable manner, and as indicated at 22. At its upper end seat member 21 has an inturned flange upon which rests the flange 23 of inlet tube 8.

As is apparent from the foregoing tube 8 is suspended from seat 21 and extends into pot 5. Air from the atmosphere passes downwardly through tube 8 and through slots 24 formed in the lower portion of the tube to commingle with the oil 10 to promote combustion.

Valve assembly 9 is arranged with respect to tube 8 for controlling the admission of air into the pot for the purpose of providing a controllable draft. This valve assembly, in the illustrated embodiment thereof, comprises a tubular casing 25 and the valve element 12 that is vertically adjustable relative to the casing 25.

Valve casing 25 telescopically fits on seat 21

and the passage of air therethrough is controlled by valve member 12. Valve member 12 is of hollow, shell-like construction, and is substantially in the form of a cone, and is easily manipulated by reason of the handle 26 provided at the base thereof.

The valve member 12 is slidably associated with valve casing 25 for movement to various positions of adjustment by reason of a pilot annulus 27 having a working fit in the valve casing, and a series of spacer bars 28 connecting the valve member 12 and annulus 27 axially spaced one from the other.

The respective opposite ends of casing 25 are flared as at 29 so that either end thereof may be used advantageously to form a seat for valve member 12 when it is desired to entirely cut off the inflow of air through the air inlet. Flaring of casing ends 29 also facilitates slewing the selected end of the casing onto seat member 21.

Stack 6 and adapter 18 are in the form of truncated cones. This is advantageous for two reasons. From the standpoint of smoke cloud production it is advantageous because, each having its major diameter at the bottom and its minor diameter at the top, there is a tendency to retard the upward movements of the smoke whereby, as regards passage of the products of combustion through the stack complete combustion results, and as regards passage of the smoke through the adapter a commingling of air and smoke just sufficient to increase the gravity of the latter for the purpose before specified is assured. From the standpoint of packing for storage and/or shipping the truncated cone form of stacks and adapters permits a number of the respective members to be nested.

Pot 5 and tube 8 are, respectively, also of tapered form, thus lending themselves, in the case of each, to compact nesting for the purposes of packing for storage and shipping.

Each of the herein described elements combining to present a smoke generator constructed and operating in the manner described may be made from sheet metal or from any other material found practical for the purpose. All components are so provided as to permit telescoping or sliding fit to effect the assembling of the parts and the securing of the assembled parts in position without recourse to fastener elements of any kind. Thus the entire smoke generator lends itself admirably to the assembly and disassembly of the separable units readily and without requiring any particular skill on the part of the operator.

From the foregoing it will be noted that the generator embodying the salient features of this invention is capable of being readily moved from place to place, is easily operated, is capable of producing smoke screens of desired quality and quantity, and in all other respects fulfills the requirements herein noted of a smoke generator suitable for the indicated purpose.

It will, of course, be appreciated that the invention is not limited to the structural details herein illustrated and described by way of example, and that the invention comprehends many variations in structure and specific mode of operation falling within the scope of the appended claims.

70 What is claimed is:

1. In a smoke generator, and in combination, a fuel pot equipped with draft control means embodying a tubular member projecting outward from the pot, and a draft control valve embodying a casing provided at each end with a flare where-

by a selected end may be used as a valve seat and the other end telescopically fitted with facility to said tubular member for mounting the valve casing on the fuel pot, and a valve element separably associated with the valve casing and having a seating part fitting one of said flared ends of the valve casing.

2. A smoke generator comprising a fuel pot having a tubular member projecting outward therefrom, a tubular valve casing provided at each end with a flare whereby a selected end may be used as a valve seat and the other end telescopically fitted with facility to said tubular member for mounting the valve casing on the fuel pot, a valve member having a conical seating part for contact with the first named end of the valve casing and a pilot element fixedly spaced axially from the seating part of the valve member and having a snug sliding fit with the casing for frictionally retaining the valve member in the desired position of adjustment relative to the valve seat-end of the said valve casing.

3. In a device of the character described, a fuel pot having a tubular member projecting outward therefrom, a valve casing provided at each end with a flare whereby a selected end may be used as a valve seat and the other end telescopically fitted with facility to said tubular member for frictionally retaining the valve casing on the fuel pot, and a valve element having a seating part fitting

5

the flared ends of the valve casing, an annulus having a sliding working fit within the valve casing, and circumferentially spaced bars respectively secured at one end thereof to the annulus and at an opposite end thereof to the valve element.

HOWARD E. NORTON.
JOHN R. BOND.
